United States Patent

Des. 234,519
Patented Mar. 18, 1975

234,519

SPLICE ENCLOSURE OR THE LIKE

Edward F. Rynk, Linden, N.J., assignor to Thomas & Betts Corporation, Elizabeth, N.J.

Filed Nov. 29, 1973, Ser. No. 420,007

Term of patent 14 years

Int. Cl. D13—03

U.S. Cl. D26—1 C

FIG. 5

FIG. 6

FIG. 7

FIG. 1 is a left side elevational view of a splice enclosure or the like showing my new design;

FIG. 2 is a front elevational view;

FIG. 3 is a rear elevational view;

FIG. 4 is a right side elevational view;

FIG. 5 is a top plan view;

FIG. 6 is a bottom plan view;

FIG. 7 is a front perspective view thereof.

I claim:

The ornamental design for a splice enclosure or the like, substantially as shown and described.
